(57) **CLAIM**

The ornamental design for a glass can, as shown and described.

DESCRIPTION

FIG. 1 is a top perspective view of the glass can showing the present design.

FIG. 2 is a bottom perspective view thereof.

FIG. 3 is a front view thereof.

FIG. 4 is a rear view thereof.

FIG. 5 is a right view thereof.

FIG. 6 is a left view thereof.

FIG. 7 is a top view thereof; and,

FIG. 8 is bottom view thereof.

1 Claim, 7 Drawing Sheets(56)

EX PARTE
REEXAMINATION CERTIFICATE

THE PATENT IS HEREBY AMENDED AS 5
INDICATED BELOW.

AS A RESULT OF REEXAMINATION, IT HAS BEEN
DETERMINED THAT:

The claim 1 is cancelled. 10
